CENTERING TOOL

Ismail Hakki, New York, N. Y.

Application April 10, 1941, Serial No. 387,989

6 Claims. (Cl. 33—191)

This invention relates to new and useful improvements in center finding and marking devices, and relates more particularly to a novel centering tool which may be used for easily, accurately and quickly determining the center of circular material and for marking such center.

Devices of this general character have been long in use, but such devices for the most part are not accurate, and the ones having a fair measure of accuracy are difficult to manipulate. It is one of the objects of the present invention to provide a device which requires no manipulation of levers, feed screws, or the like, and which may simply be placed over the end of the circular, hexagonal, square or other material, the parts instantaneously adjusted, and a pencil or an ordinary punch employed to mark the center of the material.

To this end the invention comprises a simple frame structure including a plurality of spaced, substantially square plates, one of which is provided with a central aperture in which is inserted a conventional punch for the purpose of marking the center once such aperture has been properly positioned relative to the center. The second plate constituting the frame member is provided with a relatively large central aperture through which the round material is inserted and moved into engagement with the inner surface of the other square frame member. The frame supports a plurality of pairs of extensible, substantially rectangular plates, the plates comprising each pair being movable relative to each other and are radially movable relative to the small aperture in the first plate, each pair lying at an angle to the other pair.

Each rectangular plate is formed with a substantially centrally disposed aperture which is preferably diamond shaped, two adjacent edges of which form jaw portions which engage the material at two points on its periphery. These plates which, as aforesaid, are movable relative to the frame, are initially positioned relative to such frame so that the diamond shaped apertures are in substantially the center of the frame. Then by grasping the terminals of each plate and moving the same outwardly away from the frame, the frame structure finds the center of the round material, and while so positioned a conventional punch may be inserted in the aperture in the first-mentioned plate and the center thus marked.

Whereas in the preferred embodiment of the invention the extensible plates are formed with substantially diamond-shaped apertures, it is

also within the scope of the present invention to form square apertures, in which case the device may be used for finding the center of square as well as circular material.

5 In the drawing:

Fig. 1 is a plan view of the preferred embodiment of the present invention.

Fig. 2 is a side elevation thereof, partially in section.

10 Fig. 3 is a longitudinal section taken on line 3—3 of Fig. 1.

Fig. 4 is a plan view similar to Fig. 1 but shows certain of the parts broken away.

15 Fig. 5 is a plan view showing the side of the device opposite to that shown in Fig. 1, and showing a modified form of the invention.

Fig. 6 is a perspective view of one of the rectangular plates.

20 Fig. 7 is a broken section showing a modified form of construction of the invention.

The frame structure comprises a pair of plates 10 and 11 which are rigidly mounted relative to each other in spaced relation. Both of these plates, as well as the elongated or rectangular plates, are made from relatively light gauge sheet metal, preferably aluminum. Plate 10 is formed with a small, slightly tapered, centrally disposed aperture 12, and plate 11 is formed with a large circular aperture 13. The two plates are 25 mounted relative to each other in their spaced relationship by means of specially formed screws 15 having threaded terminal portions 16 which pass through apertures (not shown) in each corner section of the plates, and which receive 30 knurled circular nuts 17.

35 Each rectangular plate 20 is formed with a substantially diamond-shaped aperture 21, two adjacent edges of which form jaw portions 22 (Fig. 6). Inasmuch as only two such adjacent edges are used at one time, the two oppositely disposed edges may be shaped otherwise if desired. The essential thing in forming aperture 21 is to provide at least two straight edges 22 which meet at a point 23, which is in alignment 40 with aperture 12 in plate 10. By providing a plurality of pairs of the plates 20, the plates of each pair having apertures with straight edges 22 which meet at point 23, which is in alignment with aperture 12, and mounting the second pair 45 for longitudinal movement at right angles to the first pair, it will be apparent that when the round material 25 is passed through aperture 13 in plate 11, through apertures 21 in movable plates 20, the plates 20 in each pair may be 50 drawn outwardly and the center of the ma-

terial is thus presented adjacent to aperture 12.

Screws 15 are desirably formed with enlarged portions 24 spaced apart a sufficient distance to receive two plates 20 therebetween. The plates 20 are preferably formed with widened flanged end portions 26 which aid in manually moving each set of plates to extended position.

In the modified structure shown in Fig. 7, the special screw 15 shown in the preferred embodiment is eliminated, and a straight screw 30 having reduced threaded end portions (not shown) is provided. In other words, screw 30 has no shoulder portions 24, and accordingly the four superimposed plates 20 and frame members 10 and 11 are in surface engagement with each other, thus making a somewhat lighter and more compact tool.

In Fig. 5 the apertures 21' are square rather than diamond-shaped, as in the preferred embodiment, and it will be accordingly apparent that when the apertures are so formed the device may be used for finding the center of square material as well as round material.

Whereas it is desired to provide the extensible plates 20 in pairs, in the manner shown, and to provide two of such pairs lying at substantially right angles to each other, it will nevertheless be appreciated that any other arrangement may be made whereby the edges 22 forming the jaw members meet at point 23 in alignment with the aperture 12 in plate 10.

What I claim is:

1. A center-finding tool comprising a plurality of spaced frame members, one having center-designating means associated therewith, and the other having an aperture therein to permit the material to be marked to pass therethrough and into substantial abutment with the inner surface of the first frame member, and means for centering the material relative to the center-designating means, comprising a plurality of centering elements slidably mounted in the frame at substantially right angles to each other, each element including a plurality of elongated, slidable plates having apertures therein forming edges for engaging the outer periphery of the material to center the same as the plates in each pair are shoved in opposite directions, and means for guiding the plates in their slidable movement comprising members connecting the frame members and engaging the longitudinal edges of the plates.

2. A center-finding device comprising a frame and a plurality of center-finding elements carried by the frame at substantially right angles to each other, said frame including spaced frame members, one having a substantially centrally disposed aperture for receiving a center-marking punch or the like, and the other having a larger aperture through which the material to be marked passes and into abutment with the inner surface of the first frame member, each center-finding element comprising a pair of elongated plates slidably mounted in the frame and having apertures therein forming edges for engaging the surface of the material, and means for guiding the plates in their movement comprising a plurality of members connecting the frame members and having recesses for receiving the longitudinal edges of such plates, and preventing rotative movement of the plates relative to the frame.

3. A center-finding device comprising a frame and a plurality of center-finding elements carried by the frame at substantially right angles to each other, said frame including spaced frame

members, one having a substantially centrally disposed aperture in which a center-marking punch may be positioned, and the other having a larger aperture through which the material to be marked passes and into abutment with the inner surface of the first frame member, each center-finding element comprising a pair of slidable, elongated plates mounted in the frame and having apertures therein forming edges for engaging the surface of the material, and means for guiding the slidable plates in their movement, comprising a plurality of pins connecting the frame members and engaging the longitudinal edges of such plates.

4. A center-finding tool for round or other shaped material and comprising a plurality of substantially flat, spaced frame members, one having center-designating means associated therewith, and the other having an opening through which the material to be marked may pass, and into abutment with the first-mentioned frame member, and means for centering the material relative to the center-designating means, comprising a plurality of centering elements slidably mounted in the frame at substantially right angles to each other, each element including a plurality of elongated, slidable plates having apertures therein, at least two edges of such apertures being angularly disposed to each other and forming jaws for engaging the outer periphery of the material, and means for guiding the plates in their sliding movement comprising members connecting the frame members and engaging the longitudinal edges of the plates.

5. A center-finding device for round or other shaped material and comprising a frame and a plurality of center-finding elements carried by the frame at substantially right angles to each other, said frame including substantially flat, spaced frame members, one of such frame members having a substantially centrally disposed aperture for receiving a center-marking punch or the like, and the other having an opening through which the material to be marked passes and into abutment with the inner surface of the first frame member, each center-finding element comprising a pair of manually movable, elongated plates slidably mounted in the frame and having substantially diamond-shaped apertures therein forming edges for engaging the periphery of the material to center the same relative to the punch-receiving aperture, and means for guiding the slidable plates in their movement comprising a plurality of members connecting the frame members and engaging the longitudinal edges of such plates.

6. A center-finding tool comprising a plurality of spaced frame members, one having center-designating means associated therewith, and the other having an opening through which the material to be marked may pass, and into abutment with the first frame member, and means for centering the material relative to the center-designating means, comprising a plurality of centering elements slidably mounted in the frame at substantially right angles to each other, each element including a plurality of elongated, slid able plates having substantially square apertures therein forming edges for engaging the outer periphery of the material, and means for guiding the plates in their sliding movement comprising members connecting the frame members and engaging the longitudinal edges of the plates.
